UNITED STATES PATENT OFFICE

WILLIAM STROBRIDGE, OF BALTIMORE, MARYLAND, ASSIGNOR TO THE BARTLETT HAYWARD COMPANY, OF BALTIMORE, MARYLAND, A CORPORATION OF MARYLAND

SEQUENCE CONTROLLING DEVICE

Application filed March 22, 1929. Serial No. 349,194.

This invention relates to automatic sequence controls for valves, and particularly to means for adjustably varying, or delaying, the action of certain valves of a controlled set.

Though not necessarily limited to this particular field, the invention will be described as applied to the device set forth and claimed in U. S. Patent No. 1,634,327, granted July 2, 1927, on the invention of James S. Kennedy.

This specific application of the device will be explained with particular reference to Figures 6 and 14 of the Kennedy patent.

In the accompanying drawings:

Fig. 1 is a vertical sectional view showing a mechanism functionally identical with that shown in Fig. 6 of the Kennedy patent with the present invention added, and illustrating the combination of the present invention with the machine disclosed in the Kennedy patent.

Fig. 2 is a plan view of the mechanism illustrated in the upper portion of Fig. 1 and showing how a plurality of independently adjustable delay units are driven simultaneously.

Fig. 3 is a face view of the adjusting dial for a delay unit such as illustrated in Figs. 1 and 2.

Fig. 4 is a perspective view of a delay unit contactor ring.

Fig. 5 is a wiring diagram showing how such a unit is connected into circuits such as are diagrammed in Fig. 14 of the Kennedy patent to delay opening of the stack valve after a run has been completed so as to purge the set to the wash box with generator blast.

In the following description all numbers lower than 300 refer to parts which appear in the identical, or essentially the identical form, in the Kennedy patent. This convention is adopted to avoid repeated reference to the Kennedy patent.

Referring first to Figs. 1 and 2 of the accompanying drawings, the master, or quarter-minute shaft is shown at 1. This shaft turns at 4 R. P. M. in the device as commercially embodied. An auxiliary quarter-minute shaft is shown at 71 and is driven

from shaft 1 at the same angular speed by spur gears 71a, 71b. The disk 76 is fast on shaft 71. The disk 72 is swiveled on shaft 71 and carries the cam extension 72a. The ball detent mechanism is shown at 77. The disk 76 is connected by a sleeve with the rotatable graduated dial 78 whose edge is knurled to permit the angular adjustment of cam extension 72a relatively to shaft 71. The adjustment is indicated by pointer 79. This conforms to the Kennedy patent in all material particulars.

Other parts will be recognized as appearing in Fig. 6 of the Kennedy patent, as follows: bar 112, spring 114, bearing support 116, pivot pin 117, bell crank 118 and its fulcrum 119, support 120, pin 121, clutch spool 122, and a part of driving pawl 2. Such minor differences in structural detail as appear involve no functional differences.

A spur gear 301 is fast on shaft 1 and drives, through idler 302 and gear 303, equal in size with gear 301, a second auxiliary quarter-minute shaft 304. The shafts 304 and 1 thus turn at equal angular speeds in the same angular direction. It thus becomes possible, without change of function, to mount the drum 126 of the "independent fifteen second switch" (erroneously numbered 125 on Fig. 6 of the Kennedy patent) on the shaft 304, and it is so shown. It could be arranged as in the Kennedy patent.

The shaft 304 is mounted in bearing 305 and drives a line shaft 306 at a 2 to 1 speed reduction ratio through the bevel gears 307 and 308. Shaft 306 is supported in bearings and drives a plurality of identical delay units. These individually may control, for example, delays in "stack opening", "generator blast closing", "stack closing", "oil valve closing", "carburetor blast valve opening", etc., as occasion may require. As the delay or time unit mechanisms are identical, only one need be described.

The shaft 306 carries bevel gears 311, each of which drives a bevel gear 312 on a corresponding shaft 313, the drive giving a 3 to 2 speed reduction. Thus the speed reduction from shaft 1 to shaft 313 is 3 to 1 and since shaft 1 turns 4 R. P. M., shaft 313 turns $1\frac{1}{3}$ 100

R. P. M., or 240° in 30 seconds, the maximum delay to be provided for in the embodiment here discussed. All the shafts 313, and there is one for each delay unit, turn at this speed.

5 Two delay units are shown in Fig. 2, each of which conforms to the following description:

Each shaft 313 is mounted in a bearing 314 and is retained by a pinned collar 315.

10 The shaft extends to the left beyond collar 315 and is formed with an annular flange 316, and near its left hand end has fixed in it a transverse pin 317 which projects at its ends.

A hollow sleeve 318 encircles the shaft and 15 its flange 316 and has a longitudinal slot 319 engaged by the ends of pin 317 to hold the shaft and sleeve against relative rotation while allowing relative longitudinal motion. The fit of the sleeve on the shaft is purposely

20 made loose to make sure that the armature will not stick. Screwed on the right end of sleeve 318 is an annular cap 321 between which and flange 316 is a thrust spring 322, for releasing the clutch.

25 Loosely pinned to sleeve 318 is the combined clutch disk and armature 323 having a dentated face 324 intended to engage a similar dentated face 325 on the right end of shaft 326, which turns in bearing 327 and is axially aligned with shaft 313.

Shaft 326 and clutch disk 323 are of soft iron and the shaft is counterbored at its end to encircle sleeve 318 which also is of soft iron. A solenoid winding 328 encircles the 35 counterbored part of shaft 326 and is enclosed by a case 329 of soft iron. When excited the solenoid draws sleeve 318 and disk 323 to the left to engage the clutch against the resistance of spring 322.

40 A coiled spring 330 constantly urges shaft 326 to rotate clockwise (as viewed from its left hand end, Figs. 1 and 2). Its initial or starting position is variably determined by an angularly adjustable stop arm 331 mounted in the front plate of the machine to turn on an axis concentric with shaft 326. The arm 331 arrests on arm 332 fast on shaft 326 and may be set in its adjusted positions by an arm 333 swinging over a dial 334 (see Fig. 50 3) and capable of being locked into selected ones of an arcuate series of holes 335 on the dial, by a screw pin 336 threaded into arm 333.

Since, as explained, shaft 313 turns 240° 55 in 30 seconds, the maximum delay to be provided for, the series of holes 335 subtends an angle of 240° and is graduated clockwise from zero to thirty seconds delay.

The case 329 supports an insulating shell 60 338 on which are two arcuate contacts 339 and 341 connected with the terminals of the winding 328. These subtend angles slightly greater than the maximum range of motion of shell 338 (in this case 240°) and positively 65 ensure, as a safety feature, deenergization of

the coil and release of the clutch at the limit of angular motion of the shell. Brushes 342 and 343 bear on these contacts.

The shell 338 also supports a slip ring 344 having a lateral extension 345. A brush 346 70 contacts constantly the main portion of the ring 344, and a second brush 347 contacts the extension 345 and thus electrically connects the brushes at the end of the delay period.

The general principle underlying the operation of the parts 301 to 345 just described, can be explained in general terms. The master shaft is running. The operator sets the lever 333 for the desired delay or time interval. In doing so he determines the initial position of shaft 326 and thus determines how far it must rotate before contact 345 engages brush 347. A switch K' Figure 5, closes a circuit through the brush 342, solenoid 328 and brush 343 at the moment from which the delay period is measured. This engages the clutch and contact 345 begins to approach brush 347. The resulting electrical connection of brushes 346, 347, establishes a second circuit through some control device, such as a stack valve motor and the response of this motor opens a switch provided for the purpose in the first-named circuit, deenergizing the solenoid, and by thus causing the clutch to disengage, allows the shaft 326 to turn 80 back to the initial position under the action of spring 330, ready for the next operation.

Connections for one particular delay function are illustrated in Fig. 5. This follows Fig. 14 of the Kennedy patent and the parts are numbered according to the convention specified. The switch operated by the stack valve solenoid P has an additional contactor 353 which in the closed position bridges contacts 351 and 352. These contacts are included in a circuit which leads from contact 215 to winding 328 to L2. Contact 215 in the closed position of the blower pressure-responsive switch K' is connected with L1. The switch 354 is the rotary switch (not numbered) which appears at the extreme right of Fig. 14 of Kennedy. 90

100 Switch K' closes when the blower has started and developed a safe pressure. This effects three results: (1) excites solenoid M to open blast valve, (2) excites solenoid 328 to engage the delay clutch, and (3) energizes contact 346 so that when finger 345 engages contact 347 the stack valve solenoid P will be actuated from closed to open position. 110

This in responding moves contactor 353 and deenergizes winding 328 so that the delay unit returns to initial position under the action of its spring. The rotary switch 354 provides for timed excitation of solenoids M and P, as provided in the Kennedy patent. 120

125 While, as above noted, two delay units are shown in Figure 2 it is to be understood that a greater number may be employed as oc- 130

casion requires and even only one may be utilized under certain circumstances so long as a time delay is desired. The time element between the operation of the various valves of a water gas set is dependent upon the variable conditions of the fuel, the fire, and other temperature conditions throughout the water gas machine.

There are certain valves which are operated through the regular water gas cycle, as noted below, through a regular sequence based on 15 second intervals as described in the Kennedy patent above mentioned. At certain times it is desirable to delay certain operations, such as the opening of the stack, the opening of the carbureter blast valve, the closing of the generator blast valve, the closing of the stack valve, the closing of the oil valve or delay the starting of the back run, or in substance any valve operation which is controlled through the electrical sequence of the automatic control, as for example, a nominal sequence of operation as follows:

25 Blow sequence:

1. Open blower steam valve.
2. Close generator steam valve.
3. Open generator blast valve.

(Delay the opening of the stack valve for a predetermined period. If this unit is in operation it acts to delay the opening of the stack cap a predetermined number of seconds for the purpose of purging the water gas set to the wash box instead of to the atmosphere.)

4. Open the stack valve.
5. Open the carbureter blast valve.

Run sequence:

6. Close the carbureter blast valve.
7. Close the generator blast valve.
8. Open the generator steam valve.
9. Close the stack valve.
10. Close blower steam valve.

45 11. Open oil valve.

(Delay closing of the oil for a predetermined number of seconds to allow the desired amount of oil to enter the set.)

- 50 12. Close the oil valve.
13. Reverse back run valve from up run to back run.
14. Reverse back run valve from back run to up run.

55 In addition to the delays above described it might be desirable to have carbureter blast opening delay or, as many operators favor, the steam purge which would require a stack closing delay, or practically any other valve delay which might be desired and included in water gas operating sequence.

60 By the presence of the electro magnetic clutching unit above set forth variation in time interval for operation may be had.

65 What is claimed is,—

1. In an apparatus for limiting the time interval of the operation of a sequence controlling device, the combination of a circuit controller arranged to open and close a circuit when moved in reverse directions; means urging said controller in one direction; means for limiting such motion; a member constantly moving in the opposite direction; an electrically actuated clutch for establishing a temporary driving connection between said member and said controller; an electrically operated device controlled by said circuit controller; a switch controlled circuit including the actuating means for said electrically actuated clutch; and an electric switch in the last-named circuit arranged to be shifted by the operation of said electrically operated device. 70

2. In a sequence controlling device, the combination of a circuit controller arranged to open and close a circuit when moved in reverse directions; means urging said controller in one direction; adjustable means for limiting such motion; a member constantly moving in the opposite direction; an electrically actuated clutch for establishing a temporary driving connection between said member and said controller; an electrically operated device controlled by said circuit controller; a switch controlled circuit including the actuating means for said electrically actuated clutch; and an electric switch in the last-named circuit arranged to be shifted by the operation of said electrically operated device. 80

3. In a sequence controlling device, the combination of a constantly moving member; a movable contactor; contacts with which said contactor coacts; means urging said contactor away from contacting position; an adjustable stop for limiting the motion of said contactor under the urge of said means; electrically actuated means for connecting said contactor with said moving member to cause it to move toward said contacts; and means for controlling the circuit through said electrically actuated means. 90

4. In a sequence controlling device, the combination of a constantly moving member; a movable contactor; contacts with which said contactor coacts; means urging said contactor away from contacting position; an adjustable stop for limiting the motion of said contactor under the urge of said means; electrically actuated means for connecting said contactor with said moving member to cause it to move toward said contacts; an electrically operated device rendered active by the closing of said contactor against said contacts; a switch controlled circuit including the actuating means of the electrically actuated means; and a switch in the last-named circuit arranged to be opened by said electrically operated device when the latter re- 100

sponds to the closing of said contactor against said contacts.

5. In a sequence controlling device, the combination of a constantly rotating member; a rotatable contactor; contacts with which said contactor coacts; means urging said contactor to rotate in a circuit-breaking direction; an adjustable stop for limiting the motion of said contactor in such direction; an electrically actuated clutch for connecting said rotatable contactor with said rotating member to cause the contactor to move toward said contacts; and means for controlling the circuit through said electrically actuated clutch.

6. In a sequence controlling device, the combination of a constantly rotating member; a rotatable contactor; contacts with which said contactor coacts; means urging said contactor to rotate in a circuit-breaking direction; an adjustable stop for limiting the motion of said contactor in such direction and thereby determining the time interval of motion of the rotatable contactor; an electrically actuated clutch for connecting said rotatable contactor with said rotating member to cause the contactor to move toward said contacts; an electrically operated device rendered operative by the closing of said contactor against said contacts; a switch-controlled circuit including the actuating means of electrically actuated clutch; and a switch in the last-named circuit arranged to be opened by the operation of said electrically operated device.

7. In a sequence controlling device, the combination of a constantly rotating member; a rotatable contactor; contacts with which said contactor coacts; means urging said contactor to rotate in a circuit-breaking direction; an angularly adjustable stop for limiting the motion of said contactor in such direction; a graduated dial for indicating the position of said stop; clamping means for fixing said stop in adjusted positions; an electrically actuated clutch for connecting said rotatable contactor with said rotating member to cause the contactor to move toward said contacts; and means for controlling the circuit through said electrically actuated clutch.

8. In a sequence controlling device, the combination of a constantly rotating member; a rotatable contactor; contacts with which said contactor coacts; means urging said contactor to rotate in a circuit-breaking direction; an angularly adjustable stop for limiting the motion of said contactor in such direction; a graduated dial for indicating the position of said stop; clamping means for fixing said stop in adjusted positions; an electrically actuated clutch including an armature, an exciting winding and a clutch member arranged to be actuated by said armature, said clutch when engaged connecting said rotatable contactor with said rotat-

ing member; and means for controlling the circuit through the winding of said electrically actuated clutch.

9. In a sequence controlling device, the combination of a constantly rotating member; a rotatable contactor; contacts with which said contactor coacts; means urging said contactor to rotate in a circuit-breaking direction; an angularly adjustable stop for limiting the motion of said contactor in such direction; a graduated dial for indicating the position of said stop; clamping means for fixing said stop in adjusted positions; an electrically actuated clutch including a winding, an armature, a dental clutch member arranged to be actuated in one direction by said armature, and a spring urging said dental clutch member in the opposite direction, the parts being so arranged that the excitation of the winding moves the armature in clutch engaging direction to establish a drive connection between said rotating member and said contactor; and means for controlling the circuit through the winding of said electrically actuated clutch.

10. In a sequence controlling device, the combination of a circuit controller arranged to open and close a circuit when moved in reverse directions; means urging said controller in one direction; means for limiting such motion; a member constantly moving in the opposite direction; an electrically actuated clutch for establishing a temporary driving connection between said member and said controller; an electrically operated device controlled by said circuit controller; a switch controlled circuit including the actuating means for said electrically actuated clutch; an electric switch in the last-named circuit arranged to be shifted by the operation of said electrically operated device; and independent means rendered effective by overtravel of said circuit controller to disengage said clutch.

11. In an apparatus of the character described, the combination of a constantly rotating shaft; an armature slidably mounted thereon and rotatable therewith; a second shaft in alignment with said rotating shaft; a solenoid winding carried by the second shaft; cooperative clutch elements associated with the armature and the second shaft respectively; an arm extending from the second shaft; and a manually adjustable stop standing in the path of movement of said arm for limiting the rotation of said second shaft.

12. An apparatus as set forth in claim 11, wherein a spring is employed for returning the second shaft to its initial angular position when the clutch elements are released.

In testimony whereof I have signed my name to this specification.

WILLIAM STROBRIDGE.

CERTIFICATE OF CORRECTION.

Patent No. 1,870,933.

August 9, 1932.

WILLIAM STROBRIDGE.

It is hereby certified that error appears in the printed specification of the above numbered patent requiring correction as follows: Page 3, lines 84, 101 and 113, page 4, lines 3, 16, 36, 51, 69 and 91, claims 2, 3, 4, 5, 6, 7, 8, 9 and 10, respectively, after the word "In" insert the words an apparatus for limiting the time interval of the operation of; page 4, line 43, claim 7, after the word "direction" and before the semi-colon insert the words and thereby determining the time interval of motion of the rotatable contactor; and that the said Letters Patent should be read with these corrections therein that the same may conform to the record of the case in the Patent Office.

Signed and sealed this 22nd day of November, A. D. 1932.

M. J. Moore,
Acting Commissioner of Patents.
